CLAIM

The ornamental design for a straw as shown and described.

DESCRIPTION

FIG. 1 is a front view of a straw showing my new design; FIG. 2 is a rear view of the straw; FIG. 3 is a right side view of the straw; FIG. 4 is a left side view of the straw; FIG. 5 is a top view of the straw; FIG. 6 is a bottom view of the straw; FIG. 7 is a top front side perspective view of the straw; and, FIG. 8 is a top rear side perspective view of the straw in use. The broken lines in FIGS. 1-4, 6, 7 and 8 depict portions of the straw that form no part of the claimed design.

1 Claim, 4 Drawing Sheets(56)
